DESIGN FOR A REAL ESTATE PHOTOGRAPH DISPLAY RACK

Harry W. Joline, Philadelphia, Pa.

Application April 13, 1937, Serial No. 68,734

Term of patent 14 years

To all whom it may concern:

Be it known that I, Harry W. Joline, a citizen of the United States, residing in the city and county of Philadelphia, and State of Pennsylvania, have invented a new, original, and ornamental Design for a Real Estate Photograph Display Rack, of which the following is a specification, reference being had to the accompanying drawing, forming a part thereof, in which:

estate photograph display rack, showing my new design;

I claim:

The ornamental design for a real estate photograph display rack, as shown.

HARRY W. JOLINE.
